UNITED STATES PATENT OFFICE.

WILBUR L. WRIGHT, OF WASHINGTON, DISTRICT OF COLUMBIA.

PAPER BOTTLE AND THE LIKE.

1,107,870.

Specification of Letters Patent.

Patented Aug. 18, 1914.

Application filed July 17, 1913. Serial No. 779,477.

To all whom it may concern:

Be it known that I, WILBUR L. WRIGHT, a citizen of the United States, residing at Washington, in the District of Columbia, have invented certain new and useful Improvements in Paper Bottles and the like, of which the following is a specification.

This invention relates to certain improvements in paper bottles, and the like; and the 10 objects and nature of the invention will be readily understood by those skilled in the art in the light of the following explanation of the accompanying drawings illustrating what I now believe to be the preferred embodiment from among other formations within the spirit and scope of the invention.

An object of the invention is to provide a 20 paper bottle or other receptacle having its paper wall at its upper end or neck flared outwardly or bell shaped by the application of a neck ring thereto, so that the neck ring rests in the bell mouth and is upheld thereby.

The invention consists in certain novel 25 features in construction and in combinations and arrangements as more fully and particularly set forth and pointed out hereinafter.

Referring to the accompanying drawings:—Figure 1, is a sectional view of the neck or mouth portion of a paper bottle or vessel showing the neck ring resting thereon preparatory to being forced down to bell the 30 mouth of the paper vessel and secured. Fig. 2, is a sectional view of the mouth or neck of the vessel after the neck ring has been forced down therein and secured thereto.

In the drawings, I show a paper bottle or other vessel wherein the surrounding upright or longitudinal paper wall 1, tapers or contracts upwardly from a comparatively 40 large base to a comparatively small neck or mouth, producing a bottle approximately frusto-conical in form, with the paper wall terminating in the top edge 2.

In carrying out my invention, I provide 45 a metal (or other suitable stiff material) annulus or neck ring or vertically arranged sleeve 3, having its lower edge bent or turned inwardly to form an approximately horizontal annular inwardly or radially projecting flange 4, extending into and surrounding the open center or bore of the ring. The upper portion of the ring flares or

50 bells upwardly and outwardly and terminates in an exterior depending annular flange 5, so that the upper portion of the ring is in the form of an inverted U. The 55 lower end portion of the ring is approximately cylindrical and is of an external diameter to permit said lower end of the ring to freely slip down into the mouth of the paper wall of the bottle about to the position disclosed by Fig. 1, of the drawings. After 60 the ring has been placed in the mouth of the paper wall to the position approximately as shown in Fig. 1, a suitably shaped plunger or presser head descends on the ring and 65 forces the same downwardly a certain distance with respect to the paper wall approximately to the position shown by Fig. 2. The ring is longitudinally or vertically 70 formed to flare or bell the mouth or neck 75 of the paper wall outwardly when forced down therein. The downward movement of the ring in the paper wall under heavy pressure, forces the neck or top edge of 75 said wall to follow the outwardly curving 80 upper portion of the ring, and thereby expands, outwardly curls or flares said portion of the wall outwardly with the ring to the form or position indicated by 7, and so that the outer annular edge portion thereof is approximately curled by and within 85 the ring. The bottle can be then rapidly rotated against a suitable spinning tool or other implement to spin tuck or turn the exterior depending free edge of the ring inwardly below and with the curled top edge portion 7, of the paper wall and thereby securely lock the ring in the bottle mouth. The flange at the lower end of the ring and located within the bottle mouth, forms a 90 sealing seat for the disks or caps generally employed as closures for milk bottles and the like. These closure disks are forced down into the lower cylindrical portion of the neck ring until seated on the flange and 95 they retain their positions in the ring by friction or by reason of the elasticity of the disks engaging said cylindrical portion.

Where the disks are applied to the bottles by capping machinery, the bottle mouths 100 are subjected to considerable downward pressure and stress and the bottle mouths must have the proper upward flare to guide the caps and plungers as well as to receive the bottle finders or centering devices of the 105 machines. The mouths of the bottles must be strong enough to withstand the vertical

thrust of the closure-disk-forcing plungers, without breaking or bending down or otherwise distorting. I accomplish this desirable result by employing the flaring neck rings with the mouths of the paper walls of the bottles bellied outwardly therein and thereby stiffened and rendered capable of resisting excessive downward pressure on the rings. The neck ring rests on and in the bell of the paper wall and hence an exceedingly strong durable structure is produced enabling the paper bottles to be successfully employed in filling and capping machinery.

It is evident that various changes, variations and modifications might be resorted to without departing from the spirit and scope of my invention, and hence I do not wish to limit myself to the exact disclosures hereof.

What I claim is:—

1. A paper wall receptacle having its mouth portion formed by a neck ring having an internal closure-seat-forming shoulder, said ring having a closure-retaining cylindrical portion above said shoulder and flaring upwardly and outwardly above said cylindrical portion and from thence extending outwardly, downwardly and inwardly to form the top edge of the bottle mouth and a projecting exterior rim around said mouth,

said ring fitting down within the paper wall of the receptacle, the upper end of said paper wall bodily flaring and curling outwardly within said projecting exterior rim, the lower exterior edge of the ring projecting inwardly below said curled portion of said wall to lock the ring on the wall.

2. A bottle having a paper material wall, and a neck ring extending down therein and forming the bottle mouth, said ring forming a sealing-disk shoulder and flaring upwardly above said shoulder and curving upwardly, outwardly and downwardly to form said mouth with a curved top edge and a projecting exterior rim, the upper end of said wall bellied and curling outwardly and downwardly within said curved top and rim of said ring to support said ring against collapse of said wall under capping and filling machine pressure on the ring and its shoulder, the exterior annular edge of said ring extending inwardly below said curled end of said wall to lock the ring thereon.

In testimony whereof I affix my signature in presence of two witnesses.

WILBUR L. WRIGHT.
